UNITED STATES PATENT OFFICE.

BENJAMIN DORIS HODGES AND CHARLES EDWARD OWEN, OF WACO, TEXAS, AS
SIGNORS OF ONE-FOURTH TO Z. A. BOOTH AND ONE-FOURTH TO HOMER J. FOWLER.

WATER HEATER.

Application filed December 29, 1924. Serial No. 758,738.

This invention relates to apparatus for heating water for domestic purposes, one of the objects of the invention being to set up the circulation of water in such a way that 5 the contents of the water container will be quickly heated and chilling of the contents by the admission of the fresh supply of cool water is practically eliminated.

A further object is to provide a heater of 10 this character which is simple, compact and efficient, and will not get out of order readily.

With the foregoing and other objects in view which will appear as the description proceeds, the invention resides in the combination and arrangement of parts and in the details of construction hereinafter described and claimed, it being understood that changes in the precise embodiment of the invention herein disclosed may be made 15 within the scope of what is claimed without departing from the spirit of the invention.

In the accompanying drawings the preferred form of the invention has been shown.

In said drawings—

25 Figure 1 is a central vertical section through the heater.

Fig. 2 is a section on line 2—2, Fig. 1.

Referring to the figures by characters of reference 1 designates a tank or casing preferably cylindrical and, in the present instance, provided with concavo-convex heads 2 and 3. A flue 4 is extended longitudinally through the tank at the center thereof and opens through and is supported by the centers of the heads. Thus when this tank is placed above a burner, the hot gases resulting from combustion will be free to flow upwardly within the flue so as thereby to heat the water within the tank at the center 35 thereof.

40 A concavo-convex partition 5 is mounted on the bottom portion of the tank and cooperates therewith to form a bottom chamber 6 into which open short tubes 7 supported by the partition and depending therefrom. A sleeve 8 is supported by this partition and is spaced from but concentric with flue 4. This sleeve has an outlet 9 at or adjacent its upper end through which water 45 rising within the sleeve is free to discharge radially into the upper portion of the tank.

50 A water supply pipe 10 extends through the upper head 2 of the tank and downwardly within the tank to a point close to the partition 5. An outlet 11 for heated

water is provided in the upper head 2 and a drain outlet 12 can be provided in the bottom of head 3.

It is to be understood that this heater is to be used above a suitable burner so that 60 the hot gases resulting from combustion will heat the bottom of the tank and also flow upwardly through the flue 4. The tank is completely filled with water supplied thereto through the pipe 10 and a portion of the 65 water is also contained in the chamber 6. As the water within the sleeve 8 is heated by contact with the flue 3 it will rise and discharge into the upper portion of the tank 1. The water thus flowing upwardly is displaced by a fresh supply admitted to the 70 chamber 6 from the tubes 7 and which, in turn, is replaced by fresh water admitted to the bottom portion of the tank from pipe 10.

It has been found in practice that by providing a heater such as described the water 75 is more quickly heated than by other means. This is due to the fact that the heated water is held away from the chilled lower portion 80 of the water in tank 1 and is not delivered into the main tank until it reaches the upper portion thereof where it will remain. Thus it is possible to obtain hot water almost instantly with a structure of this character whereas heretofore it has been necessary, to 85 heat practically the entire contents of the tank before hot water could be obtained. By providing a chamber 6, an extensive area is subjected to the heating action of the burner and as the sleeve 8 is of relatively small cross 90 sectional area as compared with the area of the chamber 6, a rapid upward flow of the heated water will be produced.

95 For the purpose of facilitating the heating of water there may be added to the structure a superheater 13 supported above the top of the tank casing 1 and preferably in the form of a hollow disk. This superheater may be supported by the pipe 10 and by the outlet pipe 14 extending from the 100 outlet 11. A pipe 15 may be used for establishing communication between the top of the super heater 13 and the pipe 14. For the purpose of conducting heated water to the super-heater, a pipe 16 is extended from the 105 chamber 6 and longitudinally of the flue 4 to the bottom of the super-heater.

110 A false bottom 17 is arranged in the tank 1 above the partition 5 so as to form a dead air space above the partition as indicated at

18. The tubes 9 extend through this dead air space and the said space serves to prevent chilling of the contents of the chamber 6 by the cold water within the tank 1. It has been found in practice that this arrangement results in a very rapid heating of the water.

What is claimed is:—

10 In a heater of the class described a tank adapted to be placed with its lower end over a heater, and a heating chamber in the lower portion of the tank, of a false bottom within the tank and spaced from the top of the heating chamber by a dead air space, a water flue extending upwardly from the top of the heating chamber and discharging at its upper end into the upper portion of the tank, water conducting tubes extending through the false bottom and opening into the lower portion of the heating chamber, said tubes being extended through but out of communi-

cation with the dead air space, a heat conducting flue extending throughout the length of the tank and opening through the ends thereof, said flue being extended through but spaced from the water flue, a hollow super-heater in the form of a baffle supported over and spaced from the upper end of the tank, a pipe connection between said super-heater and the heating chamber, said connection being located within the heat conducting flue, a water outlet pipe in communication with the upper portion of the tank and super-heater, and a water supply pipe opening into the lower portion of the tank but above the false bottom.

In testimony that we claim the foregoing as our own, we have hereto affixed our signatures.

BENJAMIN DORIS HODGES.
CHARLES EDWARD OWEN.
